UNITED STATES PATENT OFFICE.

LOUIS PHILLIPPS, OF COLUMBUS, NEBRASKA.

DRAG-SAW.

SPECIFICATION forming part of Letters Patent No. 732,958, dated July 7, 1903.

Application filed February 2, 1903. Serial No. 141,533. (No model.)

To all whom it may concern:

Be it known that I, LOUIS PHILLIPPS, a citizen of the United States, residing at Columbus, in the county of Platte and State of Nebraska, have invented certain new and useful Improvements in Drag-Saws; and I do declare the following to be a full, clear, and exact description of the invention, such as will enable others skilled in the art to which it appertains to make and use the same.

This invention relates to saw mechanism, and more particularly to interchangeable drag and circular saws and means for operating the same.

The object of the invention is to improve the construction shown in Patent No. 622,709, granted to me April 11, 1899, also to provide a device of this character which may be readily transformed from a drag-saw to a circular-saw mechanism.

With the above and other objects in view, which will readily appear as the nature of the invention is better understood, said invention consists in certain novel features of construction, combination, and arrangement of parts, as will be hereinafter fully described and claimed, reference being had to the accompanying drawings, in which—

Figure 1 is a side view of the saw. Fig. 2 is a rear view of the same. Fig. 3 is a side view of a modified form of the device. Fig. 4 is a rear view of the same.

In the drawings, 1 denotes a base, 2 a frame comprising the vertical standards 3 rising from said base and suitably braced thereto, 4 a horizontal cross-bar connecting the upper ends of the standards 3 and projecting beyond the sides of the same.

5 denotes a vertically-movable rectangular frame adjustably supported between the vertical standards 3 by means of an upwardly-projecting threaded rod or bolt 6, which is adapted to pass through a guide opening or hole, which is formed in the center of the cross-bar 4, and to receive upon its free end a threaded hand-wheel or nut 7, between which and the cross-bar 4 is a bearing plate or washer 8. It will be apparent that by rotating the hand-wheel or nut 7 the frame 5 may be raised or lowered, but will not be prevented from having at all times a free vertical movement or play.

9 denotes a main drive-shaft journaled in the side pieces of the frame 5 and passing through guide-slots 3^a, formed in the standards 3. Upon one end of said shaft is keyed a combined fly and crank wheel 10, and upon the opposite end thereof is keyed a belt or band-wheel 12.

13 denotes a counter-shaft, also journaled in the frame 5 at the lower end thereof, arranged parallel with and below the shaft 9, and upon the end of the shaft 13. Adjacent to the wheel 12 is arranged a smaller belt-wheel or pulley 14, which is connected to the wheel 12 by a belt 15. The shaft 13 also passes through the guide-slots 3^a.

On each end of the shafts 9 and 13 outside the standards 3 are mounted blocks 16. The upper blocks on each side, or those on the shaft 9, are connected to the lower blocks on shaft 13 by means of long threaded rods or bolts 17, arranged in pairs on either side of the shafts and passing through holes in the blocks 16 and held in place by nuts screwed on above and below the said blocks. The upper ends of each pair of rods 17 are connected by cross-pieces 18, to each of which is connected an upwardly-projecting rod 19, the said rods being adapted to pass through 80 guide-openings in the projecting ends of the upper cross-bar 4. The rods 19 are provided with perforations along the length thereof, which are adapted to receive pins 20, between which and the under side of the projecting 85 ends of the bar 4 are arranged springs 21, coiled around the rods 19. The tendency of the springs 21 is to force the frame 5 and the mechanism carried thereby downwardly and to yieldingly hold the same in this position, 90 the tension of the springs 21 being regulated by raising or lowering the pins 20 in the perforations in the rods 19.

22 denotes a crank-arm fixed on the extreme end of the shaft 13 adjacent to the belt-pulley 14, and to the free end of the crank-arm is pivotally connected one end of a pitman-rod 23, the opposite end of which is connected to a drag-saw 24.

25 denotes a forwardly-projecting beam or bar extending above the saw 24 and composed of two sections, an inner short section connected to the frame 5 and an outer section detachably connected to said inner sec-

tion in any suitable manner, preferably by a latch and bolts, as shown. To the beam 25 is pivoted a lever 26, having formed on its end one jaw of a clamping-dog 27, the other 5 jaw 28 of which is pivoted to the lever by the bolt which connects the same to the beam 25. The dog 28 is held pressed toward the dog 27 by means of a bowed spring 29, one end of which is fixed to the lever 26 and the opposite 10 end of which bears upon the dog 28, as shown. By this means the log to be sawed is firmly held in position to be operated on.

30 denotes a presser-arm pivotally and adjustably connected to the beam 25. The 15 outer free end of the arm 30 carries a grooved presser-wheel 31, which is adapted to be held in contact with the saw by a bowed spring 32, one end of which is connected to the beam 25 and the opposite end of which bears 20 against the arm 30.

33 denotes a saw-guide comprising a depending arm 34, having an adjustable connection with a bracket fixed on the end of the beam 25, the said bracket being provided 25 with a bolt which projects through a slot in the arm 34 and receives a thumb-nut 35, by means of which the said arm may be clamped in a raised or lowered position and is adapted to engage the outer face of the saw and 30 prevent the same from wobbling.

36 denotes an operating lever or handle pivotally connected to the crank-pin on the fly-wheel 10 and by means of which said wheel is driven.

35 37 denotes small carrying-wheels journaled on axles fixed to the base 1, and 38 denotes a tongue. By these means the device may be easily moved from place to place.

39 denotes a shelf or table detachably connected to the base 1 and standards 3.

In Figs. 3 and 4 of the drawings I have shown my machine geared to operate a circular saw 40. This is accomplished by attaching to the base 1 an auxiliary frame 41 and detaching 45 the crank-arm 22, pitman 23, and drag-saw 24 from the shaft 13, and also removing the outer end of the beam 25. The outer end of the shaft 13 is adapted to bear in the upper 50 end of the auxiliary frame 41 and to have keyed to its outer end the circular saw 40.

While I have shown the device as geared up for hand-power, it is obvious that I may readily fit the same for machine-power. When it is desired to saw down a standing tree, the 55 machine is laid upon its side, saw down, in which position it may be operated to saw a tree off close to the ground. To get different lengths of stroke to the drag-saw, I may vary the length of the pitman-rod.

From the foregoing description, taken in connection with the accompanying drawings, it is thought that the construction and mode of operation of the saw will be readily understood, and it will be seen that the device is simple and easy to operate and readily changeable from a drag to a circular saw. 65

Various changes in the form, proportion, and the minor details of construction may be resorted to without departing from the principle or sacrificing any of the advantages of this invention. 70

Having thus described my invention, what I claim as new, and desire to secure by Letters Patent, is—

1. In saw-operating mechanism, the combination with a frame comprising standards and a connecting cross-bar, said standards having elongated slots, of a vertically-adjustable frame movable between the standards, a screw-stem projecting from the vertically-adjustable frame through said cross-bar, a nut cooperating with the stem, saw-driving mechanism including driving and counter shafts in gear with each other, said shafts extending through said slots, blocks forming journals 85 for said shafts, guide-rods upon which the blocks are adjustably mounted, said rods being movable vertically in the cross-bar, and springs connected to the cross-bar and adjustably connected to the guide-rods to oppose a 90 variable yielding resistance to the upward movement of the adjustable frame, substantially as described. 75

2. In drag-saw mechanism, a supporting element carrying a log-clamp, said clamp comprising a pivoted operating-lever provided with a fixed jaw, a movable jaw pivoted to said operating-lever and formed with rack-teeth, and a spring-pawl pivoted to the lever and adapted to engage said teeth. 95

3. In saw-driving mechanism, the combination with a supporting-frame, of guide-rods adjustably mounted therein, driving and counter shafts in gear with each other, means for raising and lowering said shafts, means for adjustably connecting the same with the guide-rods, and means for opposing a variably-yielding resistance to the upward movement of the guide rods and shafts, substantially as described. 100

In testimony whereof I have hereunto set my hand in presence of two subscribing witnesses.

LOUIS PHILLIPPS.
